UNITED STATES PATENT OFFICE.

HENRY HELLMAN AND LEWIS CONDICT BAYLES, OF JOHANNESBURG, TRANSVAAL.

ROCK-DRILLING MACHINE OR ENGINE.

No. 872,418.

Specification of Letters Patent.

Patented Dec. 3, 1907.

Application filed July 12, 1905. Serial No. 269,408.

To all whom it may concern:

Be it known that we, HENRY HELLMAN and LEWIS CONDICT BAYLES, citizens of the United States, both residing at Johannesburg, Transvaal, have invented certain new and useful Improvements in or Relating to Rock-Drilling Machines or Engines, of which the following is a specification.

This invention has reference to rock-drilling machines or engines adapted to be actuated by compressed air or other elastic motive fluid.

The invention relates, to means for feeding the drill or for advancing the boring or drilling bit either by means of water or other liquid under pressure, or alternatively by means of the actuating gaseous fluid; secondly to means whereby the power utilized for feeding the drill may be varied; and our invention consists in the construction, arrangement and combination of the several operative parts of the machine as hereinafter more particularly described and defined in the claims hereunto appended.

A machine or engine constructed in accordance with our present invention operates automatically to feed the drill and to impart to the drilling or boring bit the intermittent rotary motion; the machine is of simple, efficient and compact construction. Once the machine has been brought into operation it continues to operate until it reaches the limit of its feed or movement in a forward direction when it is necessary to retract the machine and remove the drilling or boring bit and substitute it by a longer one, when the machine can again be put into operation.

A machine embodying in its construction the several features of this invention is depicted in the annexed drawing, forming part of this specification, and we will now proceed to a detailed description thereof by aid of said drawing.

Figure 1 represents the machine in longitudinal or side elevation. Fig. 2 represents it in longitudinal section. Fig. 3 is a transverse section on line $x-x$ Fig. 2. Fig. 4 is a transverse section on line $y-y$ Fig. 2. Fig. 5 is a transverse section on line $z-z$ Fig. 2. Fig. 6 is a transverse section on line $x'-x'$ Fig. 2. Fig. 7 is a transverse section on line $y'-y'$ Fig. 2. Fig. 8 is a transverse section on line $z'-z'$ Fig. 2. Fig. 9 is a transverse section on line $x-y$ Fig. 2. Fig. 10 is a transverse section on line $y-z$ Fig. 2. Fig. 11 is a transverse section on line $x-z$ Fig. 2.

In the drawing, the reference figure 1 represents the main or power cylinder, in the hollow center or bore of which is located the piston or percussive reciprocating member. 60 This cylinder at its forward end is increased in diameter.

At the forward end the main cylinder 1 is constructed with an inlet 2 which is shown formed with an internal screw thread into 65 which is screwed the throttle valve or other connection with the hose or other preferably flexible pipe conducting the actuating gaseous fluid to the machine. This inlet 2 communicates on the one side with a main supply 70 port 3, and on the other side with another port 4, hereinafter referred to, running longitudinally of the cylinder 1 in a rearward direction.

In the rear end of the main cylinder 1 is 75 screwed a cap or cover 5 which closes this end of the cylinder 1. This cover 5 on the inside is constructed with a cylindrical projection 6 which is formed with an external screw thread and screws into the internally threaded 80 rear end of the bore of the cylinder 1. Round the end of the threaded portion of the cylindrical projection 6 is formed an annular groove 7 with which the port 4 communicates—see Fig. 2. 85

The cap or cover 5 is constructed with a rearward extension 8 of square or any suitable polygonal transverse section externally, the extension 8 is inclosed by a cylinder 9 which constitutes the feed cylinder. The 90 extension 8 at its rear end is constructed with a head or cylindrical enlargement 10 which forms a piston in the bore of the feed cylinder 9. On the rear end of the piston 10 is arranged a cup leather 11 which is retained 95 in position thereon by means of a retaining bolt or plug 12 screwed into a hole in the rear end of the piston 10. The cup leather 11 serves for making a fluid tight sliding joint between the end of the piston 10 and the 100 bore of the feed cylinder 9. When the bolt or plug 12 is screwed home in the rear end of the piston 10 a space 13 is left at the bottom of the hole. Through the bolt 12 is formed a central hole 14 communicating at the one 105 end with the space 13 and at the other end opening into the interior of the feed cylinder 9 at the rear of the cup leather 11. The rear end of the feed cylinder 9 is closed by means of the back screw plug 15. 110

Encircling the feed cylinder 9 is an adjustable supporting sleeve or band 16 shown con-

structed with a conical projection 17 by means of which it may be fixed in a column clamp or any other suitable support. The sleeve 16 which is split, is formed with lugs 5 18 through which is passed a bolt 19 which serves for tightening the sleeve 16 round the feed cylinder 9.

At the forward end of the feed cylinder 9, through which works the extension 8 of 10 square or other polygonal transverse section, is fitted a cup leather 20 and gland or other suitable preferably metal ring 21, which are shaped internally to correspond to the external shape of the extension 8, the cup leather 15 20 and gland 21 forming a fluid tight sliding joint with said extension 8. In the gland cap 22 is formed a hole in which is arranged a bolt or catch 23 constructed with a piston or annular enlargement 24 fitting said hole 20 in the cap 22. Between the bottom of the hole and the annular enlargement 24 is located a spiral spring 25 which tends to keep the inner end of the bolt or catch 23 pressed against the surface of the extension 8. In 25 the forward end of the extension 8 is formed a hole or recess 26 which when the extension 8 is slid backward into the feed cylinder 9 to the end of its inward stroke, is engaged by the inner end of the bolt 23 which serves to 30 retain the extension 8 inside the feed cylinder 9. This device is provided to facilitate the changing of the drills or bits, more particularly when drilling downwardly inclined holes, the bolt 23 then serving to hold the 35 drill while the changing of the bit is effected and preventing the extension 8 sliding forward in the feed cylinder 9 by gravity during this operation. It also enables the extension 8 to be secured inside the feed cylinder 9 40 when transporting the machine or at any other time as may be desired.

In the power cylinder cover 5 is formed a screw threaded hole 27 and communicating with said hole 27 is a port 28 which port 28 45 communicates with another port 29 formed longitudinally of the extension 8 and communicates at its rear end with the space 13 in the piston 10 and through the port 14 in the bolt 12 with the rear of said piston 10. 50 Into the screw threaded hole 27 is screwed a valve 30 to which is fixed by means of the clamp 31 a hose or other suitable preferably flexible pipe 32 which serves for conducting water under pressure to the valve 30. The 55 valve 30 is constructed with a port 33 which serves for placing the source of water supply in communication with the rear end of the piston 10 through the ports 28 29 and 14. The valve 30 is also constructed with an 60 other port 34 which serves as an exhaust port by means of which the water may be drawn off from the feed cylinder 9 when it is desired to retract the machine or move the piston 10 in a rearward direction in said feed cylinder 9. In Fig. 2 the valve 30 is shown

in the position in which it is placed to open the feed cylinder 9 at the back of the piston 10 to exhaust or to draw off the water or other liquid therefrom through the port 34. By rotating the valve 30 quarter of a revolution the exhaust port 34 is closed and the main liquid supply port 33 is placed in communication with the feed cylinder 9 at the rear of the piston 10. In the cylinder cover 5 and communicating on the one side with 75 the liquid supply port 28 is another port 35. This latter port 35 communicates with an annular groove or recess 36 formed in the rear end of the main cylinder 1 or between the cylinder 1 and cover 5. In the cylinder 80 cover 5 is formed another hole 37 which forms a continuation of the port 28. The outer end of this hole 37 is provided with a screw thread and into the hole 37 is screwed a plug 38 formed with a stem 39 and piston 85 40. This piston 40 closes the hole 37 to the ports 28 and 29. It is shown in this position in Fig. 2. In the cylindrical extension 6 is formed a port 42 which places the annular recess 7 round said extension 6 in communication with the hole 37 in the cylinder cover 5 above the piston 40. As previously explained the actuating fluid which is admitted at the inlet 2 is free to pass along port 4 to the annular recess 7 and said recess 90 7 through port 42 being in communication with the hole 37, the actuating fluid is free to enter said hole 37, but the piston 40 (in the position in which it is shown in Fig. 2) prevents the actuating fluid passing beyond 95 it or entering the ports 28, 29 by which the water or liquid enters the feed cylinder 9, when water or liquid is being utilized for the purpose of feeding the drill. The screw threaded hole 37 is made sufficiently long for 100 the plug 38 to screw down sufficiently far to place the piston 40 in a recess formed by the hole 37 round the inner end of the port 28. It will be perceived that when the piston 40 is in this position it closes the port 28 and 105 shuts off the water supply to the port 29 and at the same time permits the actuating fluid to enter said port 29 and pass into the feed cylinder 9 at the rear of the piston 10. In the cylinder cover extension 8 and longitudinally thereof is formed another port 41 which at its rear end communicates with the feed cylinder 9 in front of the piston 10. This port 41 at its other end communicates with a screw threaded hole 44 in which is 110 located a screw plug 45. In Fig. 2 the two longitudinal ports 29 and 41 are in communication through the inner portion of the screw threaded hole 44 and the outer end of the screw threaded hole 44 is closed by the screw 115 plug 45. When in this position the liquid utilized for feeding the drill is free to pass both to the rear and front of the piston 10. In this position the resultant force with 120 which the drill is fed forward will be repre- 130

sented by the pressure of the liquid exerted on the difference of the areas at the two sides of the piston 10. The fluid will be admitted to both sides of the piston 10 when 5 the machine is operating in a downwardly inclined hole and when the feeding of the drill is assisted by the weight of those parts of the machine which move forward to feed the drill. When the machine is being used 10 for drilling an upwardly inclined hole it will be understood that the weight of those parts which advance to feed the drill will be acting against the pressure of the liquid in the feed cylinder 9 and to provide for this or to compensate for the weight of said moving parts 15 the plug 45 is screwed past the port 41 closing it to liquid supply and opening it to exhaust so that the liquid only enters the feed cylinder 9 at the rear of the piston 10, when 20 the full area of the piston 10 is utilized for feeding the drill.

In the cylindrical extension 6 of the cylinder cover 5 is formed a central hole 46 which opens to the bore of the cylinder 1 25 and on the rear end of the piston or reciprocating percussive member 47 is formed a cylindrical extension 48 which is of approximately the same diameter as the hole 46. On the rearward movement of the piston 47 30 this cylindrical extension 48 slides in the hole 46 and being a good sliding fit therein bottles up or confines a quantity of the actuating fluid which acts as a cushion for said reciprocating member 47 and prevents it 35 striking violently on the cylinder cover 5.

In the enlarged forward end of the main or power cylinder 1 is located a valve 49 which serves for controlling the distribution of the actuating fluid in the power cylinder 1 or for 40 alternately admitting the actuating fluid to either side of the piston or reciprocating percussive member 47 and at the same time placing the opposite end in communication with exhaust. As seen more particularly in 45 Figs. 2 and 10 the valve 49 is of cylindrical shape and is constructed with a projection 50 on one side forming flat faces 51, 52, which are utilized for reversing the valve 49 said projection 50 working in a curved recess 50 53 formed in the front end of the cylinder 1.

The cylinder 1 is, as previously stated, constructed with a main supply port 3 in communication with the fluid inlet 2. Three ports 54 serve for placing the main supply 55 port 3 under the control of the valve 49. In the cylinder 1 are formed two other ports 55, 56, which are also controlled by the valve, the one port 55, leading to the forward end of the cylinder 1 or front of the 60 piston 47 and the other one 56 leading to the rear end of the cylinder 1 or back of the piston 47, each alternately serving as supply and exhaust ports. Longitudinally of the power cylinder 1 are formed two other ports 65 57, 58, which place the recess 53 at opposite

sides of the valve projection 50 in communication with the interior of the cylinder 1. In the enlarged front portion of the cylinder 1 are formed two transverse ports 59, 60, which serve as exhaust ports for opposite 70 ends of the cylinder 1. In the valve 49 are formed two peripheral grooves or recesses 61, 62, so positioned that they alternately place the ports 55, 56, in communication with the main supply port 3 and also alternately place said ports 55, 56 in communication with the exhaust ports 60, 59. In Fig. 10 the valve 49 is shown in such a position that the port 56 which leads to the rear end of the cylinder 1, is, by means of the peripheral recess 61, in communication with the exhaust port 59, while the port 55 leading to the forward end of the cylinder 1 is by the peripheral recess 62 and ports 54 in communication with the main supply port 3 85 and closed to exhaust. In this position the piston or reciprocating percussive member 47 is moving in a rearward direction inside the cylinder 1. When the piston 47 overruns the port 58 it allows the actuating fluid at 90 the front of the piston 47 to pass along said port 58 and enter the recess 53, when, by acting on the surface 52 of the projection 50 of the valve 49 it reverses the valve and closes the port 55 to the main supply port 3 95 and opens it (port 55) to the exhaust port 60, and closes the port 56 to the exhaust port 59 and opens it (port 56) to the main supply port 3. The actuating fluid then flows along the port 56 and enters the rear end of the 100 power cylinder 1 at the back of the piston 47 and impels it on its forward and percussive stroke. When the piston 47 overruns the port 57, which it does shortly before it impinges on the inner end of the drill or bit 63, 105 the actuating fluid flows from the back of the piston 47 along said port 57 to the recess 53 and acting on the surface 51 of the projection 50 of the valve reverses the latter or returns it to the position in which it is shown 110 in Fig. 10, whereupon the rear end of the cylinder 1 is placed open to exhaust and the forward end placed in communication with the main supply port 3 as previously explained.

In the open center of the valve 49 and with its forward end fitting a recess formed in the front of the cylinder 1, is a cylindrical piece 64 constructed round its circumference with ratchet teeth 65. In a recess 66 formed inside the valve 49 is located a ratchet or pawl 67 which engages the ratchet teeth 65. The ratchet 67 is maintained in gear with the ratchet wheel or teeth 65 by means of a plunger 68 located in a hole 69 inside the recess 120 66, a spring 70 located in said hole 69 at the rear of the plunger 68 serving to keep it pressed forward on the back of the ratchet 67. The ratchet 67 and valve 49 are free to 125 rotate in one direction round the ratchet 65, 130

wheel 64 but when the valve 49 moves in the other direction it is compelled to carry with it said ratchet wheel 64 so that no motion of the valve 49 in one direction can take place 5 without the ratchet wheel 64 being rotated, which transmits the intermittent rotary motion to the drilling bit or boring tool 63.

Over the enlarged forward end of the cylinder 1 is screwed or otherwise suitably secured the front cap 71 which serves to retain the valve 49 and pawl 67 in position in the cylinder 1. The ratchet wheel 64 is constructed with a hole 72 of square or polygonal transverse section and that portion of the 15 shank of the drill or bit 63 which fits therein is made of corresponding polygonal external section so that the drill or bit 63 is compelled to rotate with said ratchet wheel 64. The drill steel 63 is constructed with an annular 20 enlargement 73 forming a shoulder which abuts the front end of the front cap 71 and insures the shank of the drill or bit 63 entering the cylinder 1 the correct distance. The cutting extremity of the bit 63 may be 25 made of any desired and suitable shape. The rear end of the shank of the drill bit 63 is made cylindrical and fits the reduced part 74 of the bore of the cylinder 1 and projects for some distance into the bore so that it receives directly on its inner end the impacts of the reciprocating percussive member or piston 47.

In the part 74 of the bore of the cylinder 1 is constructed an annular recess 75 surrounding the rear end of the shank of the drill 63. This recess 75 by means of a longitudinal port 76 is placed in communication with the recess 36 in the rear end of the cylinder 1 or between the cylinder 1 and the cylinder 40 cover 5. This recess 36, as previously explained, is placed in communication with the water supply by the port 35 so that the water may pass from said annular recess 36 along the longitudinal port 76 to the annular recess 45 75 surrounding the shank of the drill 63. A hole 77 is formed longitudinally of the drill steel communicating at the one end with the front end of the power cylinder 1 and at the other end terminating at or in proximity to 50 the cutting end of the drill 63. It is shown communicating with a central recess 78 between the radial cutting edges 79. In the steel 63 one or more ports 80 are formed which place the annular recess 75 in communication with the longitudinal hole 77 in the steel 63. These ports 80 are preferably inclined in a forward direction from the recess 55 75 to the hole 77. With this construction a quantity of the actuating gaseous fluid passes 60 from the cylinder 1 along the longitudinal hole 77 to the cutting end of the drill or bit 63. In its passage across the inner ends of the angularly disposed ports 80 it draws in by suction a quantity of water and carries it 65 along the longitudinal hole 77 to the cutting

end of the drill or bit, the water serving to prevent the formation of dust and in conjunction with the actuating gaseous fluid serving to eject the cuttings from the bottom of the hole being drilled.

Ports 81 are formed through the front cap 71 coinciding with the exhaust ports 59, 60 through which the exhaust from the power cylinder 1 may pass to the atmosphere.

The operation of the machine may be described as follows:—The feed cylinder 9 having been secured to a column clamp or any other suitable support by means of the sleeve 16 and cone 17, the main cylinder 1 is moved in a rearward direction until the piston 10 on the extension 8 takes up a position at the rear end of the feed cylinder 9. When the piston 10 is in this position in the feed cylinder 9 the spring bolt or catch 23 engages the recess 26 in the forward end of the extension 8 and so retains the parts in these positions, or the machine may be retracted in the casting 9 before being clamped to the column bar or other support. The drill or bit 63 is then loosely positioned in the front end of the power cylinder 1 with the portion of the shank which is of square or polygonal transverse section in the center of the ratchet wheel 64 and with the inner end projecting into the bore of the cylinder 1. The spring bolt or catch 23 having been disengaged from the recess 26, the valve 30 is now so positioned as to admit the water or other liquid under pressure from the hose 32 through the valve 30 and ports 33, 28, 29 and 14 to the back of the piston 10. If the hole to be bored is a downwardly inclined hole or the machine when operating is inclined in a downward direction, the plug 45 is placed in the hole 44 in the position in which it is shown in Fig. 2, or so that the port 41 is in communication with the port 29 through said hole 44. This allows the liquid under pressure to enter the feed cylinder 9 at the front of the piston 10. This results in the machine being fed forward with a pressure equal to that exerted by the liquid under pressure on the difference in the areas of the front and back of the piston 10. If the hole to be drilled is an upwardly inclined hole causing the machine to have to be inclined in an upward direction, then the plug 45 is screwed down in the tapped hole 44 until it passes the port 41 and shuts off the supply of the liquid to the front of the piston 10. The liquid being then admitted only to the rear of the piston 10 the pressure exerted by the liquid on the full area of the back of the piston 10 is utilized to feed the drill. The valve controlling the admission of the actuating fluid is now opened to admit the actuating fluid to the inlet 2 whence it passes to the main supply port 3 and according to the position of the valve 49 to one or other of the ports 55 and 56 communicating with the for- 130

ward and rear ends of the cylinder 1 respectively. The actuating fluid is free to pass along the port 4 to the annular recess 7 and from the latter by the port 42 to the hole 37 but is prevented passing beyond said hole 37 by the piston 40 when the machine is being fed by liquid pressure. The admission of the actuating fluid to either end of the power cylinder 1 impels the piston or reciprocating percussive member 47 on its outward and percussive and rearward and inoperative strokes. In its return stroke it is prevented striking violently on the cylinder cover 5 by the air pressed in the recess 46, the cylindrical extension 48 acting as a plunger on the confined fluid. On its forward stroke it impinges on the extremity of the shank of the drill or bit 63 inside the cylinder 1 and the drill or bit being loosely positioned in said cylinder 1 is thereby driven forward causing the cutting end to strike the rock face. The admission of the actuating gaseous fluid to the cylinder 1 at each reciprocation of the piston 47 permits the fluid to travel along the ports 57 and 58, which as hereinbefore fully described effects the reversal or imparts to the valve 49 its rotary motion in opposite directions and so controls the admission of the actuating fluid to said cylinder 1. The movement of the valve 49 in one direction as hereinbefore fully explained, imparts to the ratchet wheel 64 an intermittent rotary motion in one direction and the ratchet wheel transmits said intermittent rotary motion to the bit through the part of the shank which is of polygonal section and fits the hole or bore of said ratchet wheel 64. By this means the valve 49 is dependent upon the rotation taking place, that is to say the valve 49 is incapable of movement in one direction without imparting the rotary motion to the ratchet wheel 64 and drill steel 63, while it is free to rotate independently thereof in the reverse direction. A quantity of the actuating gaseous fluid passes from the front end of the main cylinder 1 along the longitudinal hole 77 in the drill steel 63 and as hereinbefore described passes to the cutting extremity along with a quantity of water which enters the longitudinal hole 77 in the drill steel 63 from the recess 75 by the port or ports 80 in the shank of the bit 63.

When the machine has reached the limit of its forward movement the actuating gaseous fluid supply is shut off and the valve 30 controlling the liquid supply is rotated quarter of a revolution to the left so as to place the back of the piston 10 in the feed cylinder 9 open to the exhaust port 34. The machine is then retracted, the liquid at the back of the piston 10 being displaced through the exhaust port 34 until the piston 10 reaches the limit of its rearward movement inside the feed cylinder 9 whereupon the

spring bolt 23 by engaging the recess 26 at 65 the front end of the extension 8 retains the parts in these positions. The drill or bit 63 is then removed and if it is desired to drill the hole deeper a longer drill or bit is then inserted in the machine and the above described cycle of operations repeated.

When it is desired for any reason to effect the feeding of the machine by means of the actuating gaseous fluid instead of by the liquid under pressure, then the screw plug 75 38 is screwed down in the hole 37 until the piston 40 takes up a position in the recess round the top of the port 28, thereby closing the inner end of said port 28 to the water supply and opening the port 29 to the hole 80 37, port 42 and recess 7, which are in communication with the actuating fluid inlet 2 through the port 4. The fluid then passes to the rear of the piston 10 and if the plug 45 is in the position shown in Fig. 2, also to 85 the front of the piston 10 to effect the feeding of the drill. By screwing down the plug 45 the port 41 is closed to the actuating fluid and opened to exhaust, when the full area of the back of the piston 10 is utilized for 90 feeding the drill. This was fully explained in connection with the liquid pressure feed.

It will be noticed that when the piston 40 is seated in the recess round the inner end of the port 28 to utilize the actuating fluid 95 to feed the drill, it does not close the liquid supply to the recess 36 so that the liquid supply to the drill or bit 63 continues.

The mechanism for rotating the drill or bit, herein shown, is not made the subject-matter of claims in this application, but constitutes the subject-matter of an application, Serial No. 321328, filed June 12, 1906, as a division of this application.

What we claim as our invention and desire to protect by Letters Patent is:—

1. In a drilling or boring machine or engine, a power cylinder containing percussive apparatus and provided with a rear extension, a feed-cylinder into which the rear extension is engaged, a piston carried by said extension, a port for supplying air to the apparatus, a port for supplying water under pressure to the rear extension, and a valve for connecting either of said ports as desired 110 to said extension.

2. In a drilling or boring machine or engine, a power cylinder having two ports leading into a third port common to both, and a valve comprising a screw and a piston, 40, 120 for connecting either of the two ports with the third port and closing the other port.

3. In a drilling or boring machine or engine, a power cylinder provided with a rear extension, a port for supplying water to the 125 rear extension, a second port for supplying water to the forward end of the power cylinder, and a valve for cutting off the supply

of water through the first named port and without stopping the supply through the second named port.

4. In feed mechanism of the class described, the combination with a motor, of means for feeding the same to its work, said means comprising a cylinder and a piston operating therein, means for conducting and admitting fluid under pressure to the cylinder on one side of the piston, and means, movable with the piston, for varying the effective pressure area of the piston acted on by such motive fluid.

5. In feed mechanism of the class described, the combination with a motor, of means for feeding the same to its work, said means comprising a cylinder and a piston operating therein, a passage-way lengthwise through said piston for conducting and admitting fluid under pressure to the cylinder at one side of the piston and means for admitting the fluid under pressure to the cylinder

der on the opposite side of the piston to vary the effective pressure area of the piston acted on by such motive fluid.

25

6. In a drilling or boring machine or engine, the combination with a main or power cylinder operatively supporting a drill or bit and a motor for rotating said drill or bit, of means for feeding said drill or bit comprising a feed cylinder and a non-rotative piston operating therein, and means for conducting and admitting fluid under pressure from the main or power cylinder supply to the feed cylinder.
